(57) CLAIM

The ornamental design for spray painter eyewear, as shown and described.

DESCRIPTION

FIG. 1 is a perspective view of a presently preferred embodiment of the spray painter eyewear of my new design from the front left thereof;

FIG. 2 is an elevational view thereof from the front;

FIG. 3 is an elevational view thereof from the rear;

FIG. 4 is a bottom plan view thereof;

FIG. 5 is a top plan view thereof;

FIG. 6 is an elevational view thereof from the left; and,

FIG. 7 is an elevational view thereof from the right.

The broken lines in FIGS. 1-7 show unclaimed subject matter, and form no part of the claimed design.
